UNITED STATES PATENT OFFICE.

JUSTUS LAUN, OF CHICAGO, ILLINOIS.

MORTAR-MIXER.

1,118,659.

Specification of Letters Patent.

Patented Nov. 24, 1914.

Application filed September 16, 1912. Serial No. 720,451.

To all whom it may concern:

Be it known that I, JUSTUS LAUN, a citizen of the United States of America, residing at Chicago, in the county of Cook and 5 State of Illinois, have invented certain new and useful Improvements in Mortar-Mixers, of which the following is a specification.

This invention relates to certain new and useful improvements in mortar mixers of 10 that type in which the mixing of materials is performed by power supplied from an explosive engine, which engine, as well as the mixing receptacle and operating mechanism, is mounted on a wheeled frame for 15 convenient and easy transportation, and it consists in certain peculiarities of the construction, novel arrangement and operation of the various parts thereof, as will be hereinafter more fully set forth and specifically 20 claimed.

The principal object of the invention is to provide a mortar mixing machine of the above named general character, which shall be simple and inexpensive in construction, 25 strong, durable, compact in form, and efficient in operation, and so made as to render the apparatus stable or firm against the shocks and vibrations incident to the operation of the engine by providing a supporting frame for the latter of I-beam construction, with the web of the I-beam frame located vertically so as to oppose the vertical 30 movements of the engine piston or pistons.

Another important object of the invention 35 is to provide means for quickly throwing the rotary mixer-shaft into gear with the engine-shaft, and in such a manner, that should any of the paddles or stirring arms on the mixer-shaft, strike an obstruction, 40 such as a stone, which is often found in the lime used as one of the ingredients of the mortar, breakage of the parts will be prevented.

Various other objects and advantages of 45 the invention will be disclosed in the subjoined description and explanation.

In the accompanying drawings which serve to illustrate an embodiment of the invention—Figure 1 is a side view with portions of the housing and mixing receptacle or trough broken away to disclose the operating and mixing mechanism; Fig. 2 is a front view in elevation; Fig. 3 is a plan view partly in section and partly in elevation, showing a part of the housing for the operating mechanism broken away, and

illustrating the mixing receptacle shortened for the convenience of illustration, but with the front axle and wheels omitted.

Like numerals of reference refer to corresponding parts throughout the different views of the drawings.

Reference numeral 10 designates the rear portion of the main or supporting frame, which portion is by preference made of an 60 I-beam formed into three sides of a rectangular figure, the open end of said portion of the frame being presented forwardly as is clearly shown in Fig. 3 of the drawings. The I-beam frame 10, is mounted at about 70 its middle on the rear axle 12, with its web 10^a, which unites its upper and lower flanges vertically, which axle is provided at each of its ends with a wheel 13, of the ordinary or any preferred construction. 75 Extended across the frame 10, at about its middle is a beam 14, on which are mounted pillow-blocks 15 and 16, in the former of which is journaled the rear end of the mixer-shaft 17, which has mounted on 80 its rear portion a gear 18, to mesh with a clutch controlled gear 19, which is mounted on a shaft 20, one end of which shaft is journaled on the pillow-block 16, and the other end thereof in a suitable journal box 85 21, mounted on a bracket 22, secured to the rear surface of the transverse plate 23, which is mounted on the front portion of the frame 10, and extended upwardly therefrom to a suitable point. The plate 23 is 90 provided on its front surface with a forwardly projecting flange 24, which is substantially U-shaped.

Mounted on the frame 10, is a housing 25, which is preferably box-like or rectangular in shape, and has in its upper portion an exhaust pipe or outlet 26, for the gases of the engine and a supply pipe 27 for water. This housing is provided on each of its sides and in its rear wall with a doorway, which 100 are closed by means of hinged doors 28, which may have hasps 29, hooks 30, and eyes 31 for fastening the same in closed positions.

Mounted vertically on the I-beam frame 105 10, within the housing 25, is a gasoline or other explosive engine, which may be of the ordinary or any preferred construction, the fly wheel 32, and shaft 33, of which only are shown.

Mounted on the front portion of the engine shaft 33, is a pinion 34, which meshes

with a gear 35, mounted on the rear end of the shaft 20, which, as before stated, is journaled in the pillow block 16, and journal box 21, so that said shaft will lie horizontally and longitudinally with respect to the machine.

Mounted on the shaft 20, between its bearings so as to rotate with said shaft is a sliding sleeve 36, which has at its rear portion 10 a grooved collar 37, to receive adjustable projections 38, such as screws, one of which is secured in each of the prongs 39, of a yoke lever 40, the prongs of which embrace the collar 37, but preferably without contacting 15 with the same. The yoke lever 40 is fulcrumed on an arm 41, which is extended forwardly and laterally from the pillow block 16, and said yoke lever is extended through a suitable opening 42, in one of the doors 28, 20 of the housing so that it may be easily reached from the exterior thereof.

Mounted at its rear end on and within the U-shaped flange 24, of the plate 23, is the mixing receptacle 57, which is trough like 25 in shape and extends forwardly from the I-beam frame 10 and constitutes a part of the supporting frame of the apparatus. The front portion of the receptacle 57, has secured to its sides the yoke 58, which is 30 pivotally connected by means of a king bolt 59, to the front axle 60, which is provided at each of its ends with wheels 13, of the ordinary construction. The front axle 60, may be provided with a tongue 61, employed 35 for transporting the machine from one point to another.

The front end of the receptacle 57, is partially closed by means of an end plate 62, in which the front end of the mixer-shaft 17, 40 is journaled, which shaft is located longitudinally and centrally within the receptacle 57, and has that portion thereof located within the receptacle formed angularly and provided with a series of radial paddles or 45 stirring arms 63, employed for mixing the ingredients comprising the mortar and for forcing the same forwardly in the mixing receptacle. The lower portion of the front end of said receptacle is provided with a 50 doorway 64, which is closed by means of the segmental door 65, to which are secured upwardly extended arms 66, which are pivotally mounted at their upper ends on a rod 67, horizontally mounted on lugs or brackets 55 68, on the end plate 62, of the receptacle. A

lever 69, fulcrumed on the rod 67, has its lower end pivotally connected to one of the arms 66, near its end, and is extended upwardly above the end plate 62, and has just above said end plate a pivoted dog 70, provided with notches 71, to engage said plate so as to hold the door 65 in open or closed positions. The end plate 62, may be provided with a journal box 72, for the front end of the shaft 17, which journal box is 65 supported on the end plate by means of a bracket 73, which is bolted to said plate.

From the foregoing and by reference to the drawings it will be clearly understood and readily seen that when the parts are in 70 the positions shown in Fig. 1 of the drawings, and assuming that the engine is in operation, the clutch mechanism will be out of engagement with the gear 19, which gear will lie idly on the shaft 20, thus imparting 75 no movement to the mixer-shaft.

Having thus fully described my invention, what I claim as new and desire to secure by Letters Patent, is—

1. A wheel supporting frame having a 80 rear frame element, of I-beam construction, a casing supported thereon and having one open end, a plate supported on the I-beam, partly closing said open end of the casing, a strap flange projecting forwardly from 85 said plate, a trough-like casing supported at its rear end on said flange, and wheels connected to the forward end of said trough-like casing.

2. A wheel supporting frame having a 90 rear frame element of I-beam construction, a casing supported thereon and having one open end, a plate supported on the I-beam, partly closing said open end of the casing, a strap flange projecting forwardly from 95 said plate, a trough-like casing supported at its rear end on said flange, said casing including a rounded bottom, a yoke contacting with the sides of the casing and projected below the bottom thereof to present a transverse strip, and wheels connected to said strip.

In witness whereof, I have hereunto subscribed my name this 12 day of Sept. 1912, in the presence of two subscribing witnesses. 105

JUSTUS LAUN.
